UNITED STATES PATENT OFFICE.

CLARENCE D. PATTERSON, OF JACKSONVILLE, FLORIDA.

FIRE DOOR.

Application filed August 18, 1923. Serial No. 658,187.

To all whom it may concern:

Be it known that I, CLARENCE D. PATTERSON, a citizen of the United States, residing at Jacksonville, in the county of Duval and State of Florida, have invented a new and useful Fire Door, of which the following is a specification.

This invention relates to fire door constructions, the primary object of the invention being to provide a door of this character which may be controlled by steam or other fluid thereby eliminating the necessity of attendants moving the door manually.

Another object of the invention is to provide means for locking the doors in their closed positions, novel means being provided for automatically releasing the doors prior to the application of the power for opening the same.

A still further object of the invention is to provide doors of this character which may if desired, be operated manually, the doors being also constructed to operate independently of each other.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a front elevational view of a fire door constructed in accordance with the invention.

Figure 2 is a side elevational view thereof.

Figure 3 is a longitudinal sectional view through the door operating pistons and housing.

Figure 4 is a longitudinal sectional view through the controlling valve.

Figure 5 is an enlarged detail view disclosing the upper portions of the doors and lower extremity of the piston operating the same.

Figure 6 is a perspective view of one of the locking dogs.

Figure 7 is a fragmental detail view disclosing the latch operating means.

Referring to the drawings in detail, the reference character 5 designates the door support which is secured to the forward por-

tion of a fire-box in place of the usual doors. This body portion is formed with a central opening indicated at 6 which opening is normally closed by the pivoted doors 7 provided with extensions 8 at their upper ends, the doors being however pivotally connected to the body portions 5 at 9 or at points laterally of a vertical line drawn through the upper extremity of the door 7.

Supported above the doors 7 and contacting with the upper extremities 8 of the doors 7, is a vertically movable piston 10 operating in the cylinder 11 which is fed with steam, through the pipe 12, that is connected with any suitable source of steam supply not shown. Pipe 12 also communicates with the cylinder 13, through the upper wall thereof, in which cylinder operates a valve 14 normally held to the limit of its downward movement by means of the coiled spring 15, the valve 14 being formed with a central opening 16 through which steam may pass on its passage to the pipe 12.

Intake pipes 17 communicate with the cylinder 13 at points adjacent to the lower end thereof, which pipes are adapted to register with the openings 18 in the valve member 14 that in turn communicates with the central opening of the valve.

The pipes 17 are in communication with a suitable source of steam supply not shown, and are supplied with valve members, not shown, for controlling the passage of steam therethrough. The valve cylinder 13 is supported on the laterally extending arm 19 which is formed with a grooved undersurface 20 in which the controlling lever 21 moves, the controlling lever being pivotally connected to the arm 19 at 22.

Forming a part of the lever 21 is a downwardly extended portion 23 having its extremity formed into a pedal 24 to receive the foot of the attendant when it is desired to manually operate the latch members to be hereinafter more fully described. Extending downwardly from the valve 14 is a rod 25 that has pivotal connection with the lever 21 as at 26, whereby movement of the lever will result in a relative movement of the valve 16 or vice versa.

As shown, the lower portion of the body 5 extends downwardly at 27 and is formed with a suitable opening to receive the shaft 28, the ends of which extend beyond the guide members 29 formed integral with the

extension 27, and between which guide members the lugs 30 pass, the lugs being carried by the doors.

Mounted on the extended ends of the shaft 28 are latch members 31 that move with the shaft and act to restrict movement of the doors when the doors are in their closed positions, the latch members 31 being of construction to engage the outer edges of the lugs 30 and prevent pivotal movement of the doors.

Secured to the piston 10 is a connecting plate 32 to which is connected the right angled extremity 33 of the operating rod 34, which rod moves through the bearings 35 and 36 that are arranged in spaced relation with each other. Extending laterally from the rod 34 are pins 37, which pins are engaged by the hook members 38 of the operating lever 39 that has one end thereof, pivotally connected to the lower bearing 35 through the upwardly extended arms 40.

From the foregoing it will be obvious that as the operating lever 39 moves downwardly, the controlling rod 34 is also moved downwardly to move the doors 7 to their open positions. Associated with the lever 39 is a keeper 41 to cooperate with the latch member 42 and hold the lever 39 in various positions of adjustment.

Secured to one end of the shaft 28 is an arm 43 which when moved operates to move the latch members 31 to their inactive positions.

A rod 44 connects the arm 43 and the lever 21 so that upon movement of the lever 21 in one direction, the latch members 31 will be moved to their inactive positions and out of

the path of travel of the lugs 30, allowing the doors to move to their open positions.

If it is desired to move the doors independently of each other, handles 45 are formed on the doors which handles provide means to be gripped by the operator.

I claim:

1. In a device of the character described, a door support, a pair of doors pivotally mounted on the support, a piston moving above the doors, and adapted to engage the doors for moving the doors to their open positions, pivoted latch members disposed adjacent to the lower ends of the doors, means for actuating the latch members to release the doors upon movement of the piston to open the doors, and said latch members adapted to automatically engage the doors and hold the doors in their closed positions.

2. In a device of the character described, a door support, a pair of pivoted doors mounted on the support, means above the doors for moving the doors to their open positions, said doors having lugs extending downwardly therefrom, guide members co-operating with the lugs to hold the doors to the door support, and latch members adapted to engage the lugs for normally holding the doors in their closed positions.

In testimony that I claim the foregoing as my own, I have hereto affixed my signature in the presence of two witnesses.

CLARENCE D. PATTERSON.
